UNITED STATES PATENT OFFICE.

PIERRE DUVINAGE, OF BROOKLYN, NEW YORK.

STEP FOR SPIRAL STAIRWAYS.

1,215,352.

Specification of Letters Patent. Patented Feb. 13, 1917.

Application filed December 2, 1915. Serial No. 64,728.

To all whom it may concern:

Be it known that I, PIERRE DUVINAGE, a citizen of the United States, residing at New York, borough of Brooklyn, in the county of 5 Kings and State of New York, have invented a new and useful Step for Spiral Stairways, of which the following is a specification.

This invention relates to steps for spiral stairways used in buildings, fire escapes, 10 and other places where it is desired to have a stairway which will occupy comparatively little space; and the object of my invention is to provide a step made of cast material so constructed that each step will have the necessary 15 sustaining strength when supported at the inner end only and at the same time a stairway will be provided all parts of which will be available for ascent or descent; a further object of my invention being to provide 20 a step so constructed that but a single pattern will be needed in building either a "right" or "left" stairway.

The invention is illustrated in the accompanying drawing, in which—

25 Figure 1, is a longitudinal vertical section of a step constructed in accordance with my invention, the supporting riser being shown in full lines;

Fig. 2, is a transverse section of the step, 30 on the lines 2—2, of Figs. 1, and 3;

Fig. 3, is a plan view of the step, with a portion of another step superimposed thereon, illustrating how the steps are arranged in a stairway winding to the right in as- 35 cent; and

Fig. 4, is a view similar to Fig. 3, showing how the steps are arranged winding to the left in ascent.

In the drawing, like numerals of refer- 40 ence refer to the same parts in each of the views.

In practice I provide a step consisting of a tread 5, comprising a divergent part 6, and a part 7, with substantially parallel 45 sides ending in a hub 8, with a cylindrical passageway 9, therethrough whereby means are provided for mounting the step on a vertical shaft, as will be understood; and each step may have a boss 10, arranged in 50 any desired position, each having a passageway 11, through which a set screw may pass to engage the shaft, or column on which the step is mounted, whereby the step will be held in fixed position, as will be understood.

55 The step is provided with a central rib, or riser 12, which extends from the hub 8,

to the outer end of the step, as clearly shown in Fig. 1. As the hub 8, has considerable length, the riser 12, extends downward a considerable distance on the same 50 without interfering with the step below, and can rise from this point to the outer end of the step in a manner to form a firm brace, or support for the tread thereby making it unnecessary to support the step at the outer 55 end, as will be clear.

The step is also provided with ribs 13, and 14, which extend respectively on the opposite sides of the flaring part 6, in a substantially radial manner from the center of the 70 hub 8, or axis thereof, as the inner edge of each rib is on a radial line from the axis of the hub; and the outer ends of the ribs 13, and 14, are connected by a rib 15, whereby the entire step is strengthened, as will be 75 understood.

The edges 16, and 17, of the step converge toward the hub 8, till they meet respectively the edges 18, and 19, which are tangential to the periphery of the hub; and the ribs 13, 80 and 14, meet respectively the ribs 20, and 21, which are spaced respectively the same distance from the edges 18, and 19, of the part 7, that the ribs 13, and 14, are spaced from the edges of the part 6. 85

In mounting the steps in place the rib 13, of one step is mounted directly above, or below the rib 14, of the next step, according as the steps wind to the right or left, which can be readily done since the ribs are substantially 90 radially disposed on the steps. This provides for the necessary lapping of the edges of the successive steps, the proper stiffening of the step where the greatest strain occurs, and the most effective exposure of each step for the foot. 95

As each step comprises the flaring part 6, and part 7, with parallel sides, when the steps are superimposed, as in a stairway, with the successive ribs 13, and 14, vertically disposed, as clearly shown in Figs. 3, and 4, one of the parallel edges 18, or 19, of the parallel part will transversely extend across the face of the step below substantially parallel with a tangent of the stairway, as clearly shown in Figs. 3 and 4. By this construction, a person walking down the stairway adjacent to the inner post, will have his steps directed toward the periphery of the stairway, as the edge of the step 105 adjacent the central post is parallel with a tangent of the stairway, and it is natural to 110

step from a step facing the edge. Following this tendency would carry the person outward toward the periphery of the stairway, as will be understood, where the tread 5 surface of the step is broader. Thus, by making the inner portion of the step with edges tangential to the hub, and parallel with each other, and, consequently, parallel with a tangent of the stairway, I provide a 10 stairway that is easier to ascend, or descend close to the central post thereby greatly increasing the capacity of the stairway, and reducing the necessity of lengthening the steps for the sake of capacity. This also reduces the liability of any object sliding down the stairway for the reason that when 15 the object leaves one step, as here constructed, it will be directed toward the periphery of the stairway more than would be the case if the edges of each step extended 20 radially from the hub, or even in a straight line tangentially from the hub to the outer end.

By making the steps in the way de- 25 scribed, the same pattern can be used for all

the steps whether the steps wind to the right, or left in ascending, as will be clear.

The step is simple in construction, easy to manufacture, and efficient in use.

I claim:

1. A step for a spiral stairway, said step having a hub, and having edges adjacent to said hub parallel to each other and extending a sufficient distance from the hub that a perpendicular erected thereto will traverse 35 the periphery of the second lower step in a stairway, said step having edges diverging from said parallel sides.

2. A step for a spiral stairway, said step having a hub, and having parallel edges adjacent to the hub and tangential thereto, said edges extending a sufficient distance from the hub that a perpendicular erected thereto will traverse the periphery of the second lower step in a stairway, said step 40 having edges diverging from said parallel sides.

Dated this 30th day of September, 1915.

PIERRE DUVINAGE.
